UNITED STATES PATENT OFFICE.

ROBERT L. HARRIS AND GLENN B. SMITH, OF JACKSONVILLE, FLORIDA.

RAILROAD-CROSSING SIGNAL.

1,311,970.

Specification of Letters Patent.

Patented Aug. 5, 1919.

Application filed October 29, 1917. Serial No. 198,948.

To all whom it may concern:

Be it known that we, ROBERT L. HARRIS and GLENN B. SMITH, citizens of the United States, residing at Jacksonville, in the county of Duval and State of Florida, have invented new and useful Improvements in Railroad-Crossing Signals, of which the following is a specification.

This invention relates to signal devices especially adapted for use in connection with railroad crossings.

In signal devices as heretofore constructed for the above purpose, it has been the aim to warn of the approach of a train by means of a device usually automatically operated by said train.

The present invention in addition, aims to provide means for automatically operating the signal by a vehicle approaching the track, so that the occupants thereof will be warned of the presence of the railroad in time to take the proper precautions for safety.

The invention also consists of the following novel construction and arrangement of parts, hereinafter more fully described and illustrated in the accompanying drawings, wherein—

Figure 1 is a transverse sectional view taken through the vehicle operated member and its housing;

Fig. 2 is a fragmentary sectional view on the line 2—2 of Fig. 1;

Fig. 3 is a vertical sectional view through the alarm mechanism;

Fig. 4 is an enlarged sectional view on the line 4—4 of Fig. 3;

Fig. 5 is a view similar to Fig. 1, but illustrating a modified form of the invention; and

Fig. 6 is a sectional view on the line 6—6 of Fig. 5.

Fig. 7 is a fragmentary cross sectional view showing the antifriction means for the vertical movable signal actuating member.

Referring in detail to the drawings, wherein like characters of reference denote corresponding parts, there is shown a casing or housing which is designed to extend transversely across the roadway and be positioned at a suitable distance from the railroad track. This casing or housing includes a bottom 10, sides 11 and top 12, the latter being arranged substantially flush with the surface of the roadway. The top

is formed with a longitudinally arranged slot 13, which extends substantially throughout the length of the housing, the sides of this slot being reinforced by means of angle plates 14 to prevent wear.

The slot 13 is positioned along one edge of the top of the housing and operating in this slot is a vertically movable member 15. This member is of an inverted U shape in cross-section and has secured therein spacing elements 16, the lower ends of which are provided with depending lugs 17. These lugs are adapted to engage openings 18 formed in laterally extending arms 19 carried by a rock shaft 20. An annular flange 21 is formed on the lug 17, one face of which is adapted to engage the arm 19 to depress the same, when the vertically movable member 15 is depressed. This engaging face is rounded as shown at 22 and is adapted to operate in a seat 23 surrounding the opening 18. In order to prevent the withdrawal of the lug 17 from the opening 18, there is employed a cotter pin 24 upon the lower side of the arm 19.

The rock shaft 20 extends throughout the length of the housing and is adapted to operate in bearings located therein, these bearings consisting of the section 25 and section 26, both of which are bolted together and to the housing by means of lag bolts 27.

One end of the rock shaft 20 enters the signal casing 28 and has secured thereon an arm 29, which is adapted to move in unison with the arm 19.

Pivotedly secured to the outer end of the arm 29 is a vertically disposed rod 30, which is guided in the bracket 31 secured to the side of the casing 28. The upper end of the rod 30 is provided with a notch 32, which is adapted to engage a lever 33, pivoted intermediate its end as shown at 34. The lever 33 is formed with a beveled end 35 for engagement with the notch 32 in the rod 30, the lever 33 being held in a position to retain the rod 30 elevated by means of a spring 36 secured to the end opposite the beveled end 35. The spring 37, one end of which is secured to the casing and the opposite end to the arm 29, serves to hold the rock shaft 20 in position to normally maintain the vertically movable member disposed above the surface of the roadway in position to be acted upon by a crossing vehicle. The rod 30 is provided with a longitudinally curved portion 38, located

- immediately below the notch 32 and adapted to form a cam for engagement with the guiding brackets 31, so that when the shaft 20 is rocked to pull downward the rod 30 5 the same will be disengaged from the lever 33 as shown by dotted lines in Fig. 3. A stop 39 located in the path of movement of one end of the lever 33 serves to limit the movement of this lever in one direction.
- 10 Secured to the lever 33 adjacent the pivot 34 is a flexible rod 40, the outer end of which carries a clapper 41 for contact with a gong 42, so that when the lever 33 is released from its engagement with the rod 30 the spring 15 36 will cause the clapper 41 to strike the gong 42 and due to the flexibility of the rod 40 the vibrations of this rod will be continued for an appreciable length of time and continue to sound the gong. The spring 43 20 having one end secured to the rod 30 and its opposite end to the casing 28 serves to pull the said rod into a position to cause the curved portion or cam 38 to bear against the bracket 31 when the guide is operated.
- 25 In order to provide for the operation of the signal by an approaching train, there are provided magnets 44 positioned within the casing 28, the said magnets being adapted to operate a pivoted armature 45, which 30 has connected thereto an extension 46, the lower end of this extension resting upon the upper edge of the lever 33 while a stop 47 is located in the path of movement of the said extension to properly position the armature with respect to the core of the 35 magnets.

When there is a train in the bounded section of the rails, the magnetism of the coil 44 will hold the armature up and prevent 40 the movement of the lever 33 upon its pivot. When the magnet is deenergized by a train entering the bounded section of the track, the armature 45 will drop by its own weight to the position shown in dotted lines in Fig. 45 4, permitting the spring 36 to operate the lever 33 to sound the alarm.

When the armature 45 is again raised by the action of the magnets 44, the notched end of the lever 30 will be engaged with the 50 pointed end 35 of the lever 33 through the action of the spring 43, which draws the rod 30 over for this purpose. This action of the armature will also cause the extension 46 to engage the lever 33 and the signal will 55 be locked against operation.

In the modified form of the invention as shown in Figs. 5 and 6, the vertically movable member consists of a bar 48, which is inverted U shape in cross-section and is 60 adapted to operate within a slot 49 formed by a casing 50 located flush with the road-

way. The bar 48 is held in a raised position by means of a wishbone spring 51, the upper movement of the bar being limited by the engaging member 52 located at the end 65 of the housing 50 and provided with an angular extension 53 located in the path of movement of the bar 48. The downward movement of the bar 48 is limited by the stops 54.

One end 55 of the bar 48 is adapted to extend within the casing 28 and to have pivoted thereto as shown at 56 one end of the rod 30, the construction and operation of the alarm mechanism being the same as described in the previous form of the invention.

To provide anti-friction means between the casing 10 and the vertically movable member 15, the latter carries a plurality of 80 rollers 60, disposed longitudinally of the said member and arranged in a manner to bear against one of the angle plates 14. This permits free movement of the member 15, overcoming any tendency to bind, which 85 may result in the failure of the signal to operate. The casing 10 is strengthened throughout its length by means of transversely arranged spaced supports 61, which also provide additional bearings for the 90 shaft 20.

It is believed that from the foregoing description when taken in connection with the accompanying drawings, the construction, operation and advantages of the invention 95 will be apparent. The right is reserved to make such changes in the form and proportion thereof as will fall within the scope of the claims hereto appended.

Having described the invention, what is 100 claimed is:

1. A signal device embodying a vertically movable member arranged transversely across a roadway and adapted to be depressed by a vehicle, a signal and means including a spring actuated lever released by said member for operating the signal.

2. A signal device embodying a vertically movable member mounted transversely across a roadway and adapted to be depressed by a vehicle, a rock shaft operated by said member, a rod mounted for reciprocation and operated by the rock shaft, a spring actuated pivoted lever having one end detachably engaging a notch in said rod 110 and operated by the latter against the tension of the spring and a signal operated by said lever.

In testimony whereof we affix our signatures.

ROBT. L. HARRIS.
GLENN B. SMITH.
